Adolph T. Johanson

By Walter M. Fuller
Atty.

UNITED STATES PATENT OFFICE

ADOLPH T. JOHANSON, OF CHICAGO, ILLINOIS

BOILER

Application filed January 9, 1931. Serial No. 507,554.

My invention pertains to certain novel features of construction and improvements in the manner of functioning in boilers, heaters, garbage incinerators, and the like, and one of its leading aims is to provide a structure of this character having two grates with associated walls or baffles, preferably water heating, whereby the appliance may operate with efficiency and economy.

10 A further salient feature of the invention resides in the fact that the baffle walls are permanently fixed in place, whereby they cannot become displaced or dislodged during shipment or transportation, and they are arranged substantially vertically, in the preferred embodiment of the invention, so that they are largely, if not entirely, self-cleaning; meaning by that, that the soot tending to find lodgment thereon naturally falls off because of the upright disposition of the barriers.

To enable those acquainted with this art to understand the invention fully, in the accompanying drawings, constituting a part of this specification, and to which reference should be had in connection with the following detailed description, a desirable embodiment of the invention in physical form has been depicted, and, for simplicity, like reference numerals have been employed to designate the same parts throughout the several views.

In the drawings:—

Figure 1 is a longitudinal, central, vertical section through the boiler on line 1—1 of Figure 3;

Figure 2 is a vertical cross-section on line 2—2 of Figure 1; and

Figure 3 is a vertical cross-section on line 3—3 of Figure 1.

40 Arrows have been associated with the specified section lines to indicate the direction in which the parts are viewed in connection with such sections.

Referring to the drawings, it will be perceived that the new boiler or equivalent apparatus includes a hollow base 11 divided by a transverse partition wall 12 into two ash pits or chambers 13 and 14 equipped with doorways and associated doors 15 and 16, respectively.

Supported on such underlying base is the boiler proper having a metal sheet bent to form the two, outer side-walls 17 and 18 and the curved or rounded, top, exterior wall 19, flanged end-walls 21 and 22 being welded to such wrapper sheet in the usual manner.

Inside of, and spaced inwardly away from, such outer, metal sheet or wall, a smaller, similar metal sheet is located having side-walls 23 and 24 and an upwardly-arched, top section 25, whereby side water-legs 26 and 27 are provided, such formed or bent sheet being welded around its edges to flanges of front and rear wall plates 28 and 29, respectively, the margins of inwardly-projecting flanges 31 and 32 along the lower edges of the outer walls 21 and 22 being welded to the adjacent surfaces of the inner end-wall plates 28 and 29 to close the bottoms of the front and rear water-legs 33 and 34, analogous flanges 35 and 36 at the lower borders of the outer walls 17 and 18 being likewise welded to the companion, inner walls 23 and 24, all as is clearly illustrated.

Horizontal, transverse water-tubes, in four groups, 37, 38, 39, 40, extend through aligned apertures in the inner walls 23 and 24 and thus connect or join the water-legs 26 and 27 together.

About midway of the length of the structure, an upright, hollow, thin or shallow, water-wall 41 connects the two side water-legs 26 and 27 together, such wall being made of sheet-metal which fits in correspondingly-shaped, rectangular openings in the plates 23 and 24 to which its margins are welded, such water-heating cross-wall extending about three-fourths of the way from the bottom of the compartment in the boiler to its top.

Such cross or transverse water-wall divides the boiler into two, fuel-combustion boxes or chambers 42 and 43, the one having a fire-box doorway and door 44, and a cleanout doorway and door or closure 45 at one end of the boiler, the other chamber having a comparable doorway and door 47 in one side of the boiler and a cleanout aperture and cover 48 in the other end-wall.

Chamber 42 has a grate 49 and the compa- 100

ion or correlated chamber 43 is fitted with a similar grate 51.

As is clearly presented, the upper portion of the double back-wall 22, 29 has a flue or connection 52 to convey the products of combustion to the chimney or stack, not shown, and such conduit is equipped with the customary damper 53.

The opposite end-wall of the structure has a similar or like flue or conduit 152 for the escape of the hot combustion gases to the stack or chimney and such passage is fitted with a damper 153.

About midway between the intermediate wall 41 and the rear wall 22, 29, the structure is provided with a hollow, water-filled barrier or baffle 54 open at its top and ends to the water space of the boiler above the curved sheet 25 and to the side water-legs 26, 27, the margins of the sheet-metal walls of such part 54 being welded around the border of the appropriately-shaped openings provided in the inner bent plate 23, 24, 25, the bottom of such barrier or deflector being closed in any approved manner, as by a flange 55 on one of the barrier side-plates, whose margin is welded to the opposite side-plate.

Barrier 54, above the water-tubes 39 and 40, has a horizontal opening or passage 56 therethrough fitted with a rocking damper 57, the opening and closing or adjustment of which may be effected by any convenient means, not shown.

A similar, water-charged, vertical, depending baffle 154 with a port 156 and damper 157 therefor is located between the groups of tubes 37 and 38, but, in the present instance, it does not extend down quite so far as the companion barrier 54.

It will be noted that the cross-wall 41 extends upwardly from the grates to the tops of the uppermost row of transverse water tubes or pipes, that the barrier 54 continues down to the bottoms of the lowermost series of such pipes or tubes, and that the baffle 154 is somewhat shorter.

Dampers 53 and 157 are connected together by a link 257 so that they work together, and dampers 153 and 57 are similarly united by a link 50, compelling them to operate in unison.

When damper 53 is open, damper 157 is likewise open, and, conversely, when either of such dampers is closed, the other necessarily is closed; and, comparably, when damper 153 is open, damper 57 is also open, and when one of such dampers is closed, both are necessarily closed.

Such pairs of dampers may be rocked to open or to close them by any approved means.

Either grate may be used singly for the burning of fuel or for the incineration of garbage or refuse, or both grates may be em-

ployed conjointly for such fuel combustion, or refuse disposal.

When the front grate 49 is made use of for the burning of fuel, with the rear grate 51 either idle or employed for the disposal of garbage or the like, the damper 57 is usually closed and the damper 157 open, thereby allowing the combustion gases to flow up between the water-tubes 37 and 38, a portion of such gases passing through the open port 156, and all of the gases flowing over the top of wall 41, down between the tubes 39, around the lower end of barrier 54, up between the pipes 40, and out to the stack through the open exit or discharge flue 52, it being understood that under these conditions flue 152 is closed.

Obviously, under such circumstances, the hot gases comes into contact with all of the tubes, all of the walls of the boiler, including the cross or division wall 41, and the barriers 54 and 154, which results in an efficient and economical operation of the appliance.

If the rear grate 51 is used alone for the burning of fuel, with the front grate 49 either idle or used for the incineration of garbage, it is customary to open the damper 57 and close damper 157, and to open flue 152 and close flue 52, so that the combustion gases will pass up between the tubes 39 and 40, those flowing between the tubes 40 passing through the port 56, and all the gases flowing over the wall 41, down between the tubes 38, around the lower edge of barrier 154, up between the tubes 37, and out of flue 152.

Again, fuel may be burned on both grates at the same time, and, in such case, the products of combustion may be discharged through either flue 52 or 152 alone, or through both of such flues, both being partially open, in the latter instance, and the dampers 57 and 157 arranged correspondingly.

Further, either grate may be used singly for the burning of fuel with the delivery of the gaseous products of combustion to its adjacent flue 52 or 152, as the case may be, and with the corresponding port 56 or 156 open.

Of course, in that case, the boiler is being operated at only partial capacity, but even then comparatively economically.

From the foregoing, it will be clear that this particular embodiment of the invention provides a double-grate, double combustion-chamber boiler with water-tubes and walls or barriers so arranged and disposed as to permit the structure to be operated in any one of several ways, and, at the same time, preserve its capacity for efficient functioning, regardless of the particular manner in which it is worked.

All parts of the appliance, including the cross-wall and depending barriers, are fixed permanently in place, whereby there is no danger of their displacement or dislodgment

during shipment or installation of the boiler or heater, and, by making such wall and deflectors hollow and connecting their interiors in the manner illustrated and described, their 5 contents become heated and the circulation of the water in the boiler is augmented in a manner to increase the operating efficiency of the apparatus.

Furthermore, since such transverse walls 10 are arranged vertically, they are self-cleaning, in that any soot or the like tending to settle or become deposited thereon automatically falls off down on to the grate or grates where it is burned.

15 This invention is not limited or restricted to the exact details of structure shown and described, and many mechanical changes may be incorporated in it without departure from the invention, as defined by the appended 20 claims, and without the loss of any of its material benefits or advantages.

For example, instead of using a grate for 25 the combustion of fuel, other means for burning other types of fuel, such as powdered or pulverized coal, oil, gas, or the like, may be substituted.

I claim:

1. In a boiler, the combination of outer side and top walls, inner side and top walls spaced 30 from the corresponding outer walls to provide a water-reservoir, end-walls for the boiler, water-tubes extended across the compartment defined by said inner walls and connecting together the water-legs between said side-walls, 35 a transverse wall connecting together said inner side-walls and extended upwardly from the bottom of said compartment between and to about the top of said water-tubes and dividing said compartment into two chambers, 40 said wall terminating short of the top of said compartment, a grate in one of said chambers below said tubes, means below the tubes in the other chamber to co-operate with fuel in a manner to facilitate its combustion, 45 a discharge-flue connecting with the upper portion of one of said chambers, a barrier depending from the top of that chamber equipped with said discharge-flue, said barrier extending down between the water-tubes in such chamber, said barrier having an opening therethrough, and a damper for said opening.

2. In a boiler, the combination of outer side and top walls, inner side and top walls spaced 55 from the corresponding outer walls to provide a water-reservoir, end-walls for the boiler, water-tubes extended across the compartment defined by said inner walls and connecting together the water-legs between said side-walls, 60 a transverse wall connecting together said inner side-walls and extended upwardly from the bottom of said compartment between and to about the top of said water-tubes and dividing said compartment into two chambers, said wall terminating short of the

top of said compartment, a grate in one of said chambers below said tubes, means below the tubes in the other chamber to co-operate with fuel in a manner to facilitate its combustion, 70 a discharge-flue connecting with the upper portion of one of said chambers, a hollow water-barrier depending from the top of that chamber equipped with said discharge-flue, said barrier extending down between the tubes in such chamber and connecting at its ends with said water-reservoir, said barrier having an opening therethrough, and a damper for said opening.

3. In a boiler, the combination of outer side and top walls, inner side and top walls spaced 80 from the corresponding outer walls to provide a water-reservoir, including water-legs between said side-walls, end-walls for the boiler, water-tubes extended across the compartment defined by said inner walls and connecting said side water-legs together, a hollow transverse water-wall connecting said side water-legs together and extended upwardly from the bottom of said compartment to about the top of said tubes and dividing 85 said compartment into two chambers, said wall terminating short of the top of said compartment, a grate in one of said chambers below said tubes in the other chamber to co-operate with fuel in a manner to facilitate its combustion, 90 a discharge-flue connecting with the upper portion of one of said chambers, a hollow water-barrier depending from the top of said chamber equipped with said discharge-flue, said barrier extending down between the water-tubes in such chamber, and connecting at its ends with said water-reservoir, said barrier having a port therethrough above said water-tubes, and a damper for said port.

4. In a boiler, the combination of outer side and top walls, inner side and top walls spaced 95 from the corresponding outer walls to provide a water-reservoir between them, end-walls for the boiler, water-tubes extended across the compartment defined by said inner walls and connecting together the water-legs between said side-walls, a transverse wall connecting said inner side-walls together and extended upwardly from the bottom of said compartment between and to about the top of said water-tubes and dividing said compartment into two chambers, said wall terminating short of the top of said compartment, 100 a grate in one of said chambers below said tubes, means below said tubes in the other chamber to co-operate with fuel therein in a manner to facilitate its combustion, a discharge-flue for and connecting with the upper portion of each of said chambers, dampers for said flues, a baffle depending from the top of one of said chambers and extending down between the tubes in said chamber, said baffle having a port therethrough, and a damper in 105 said baffle port.

5. In a boiler, the combination of outer side and top walls, inner side and top walls spaced from the corresponding outer walls to provide a water-reservoir between them, end-walls for the boiler, water-tubes extended across the compartment defined by said inner walls and connecting together the water-legs between said side-walls, a transverse wall connecting said inner side-walls together and extended upwardly from the bottom of said compartment between and to about the top of said water-tubes and dividing said compartment into two chambers, said wall terminating short of the top of said compartment, a 10 grate in one of said chambers below said tubes, means below the tubes in the other chamber to co-operate with fuel therein in a manner to facilitate its combustion, a discharge-flue for and connecting with the 15 upper portion of each of said chambers, dampers for said flues, a baffle in each of said chambers depending from the tops of the respective chambers and extending down between the tubes in such chambers, said baffles 20 having ports therethrough, and dampers in 25 said baffle ports.

6. In a boiler, the combination of outer side and top walls, inner side and top walls spaced from the corresponding outer walls to 30 provide a water-reservoir between them, end-walls for the boiler, water-tubes extended across the compartment defined by said inner walls and connecting together the water-legs between said side-walls, a transverse wall 35 connecting said inner side-walls together and extended upwardly from the bottom of said compartment between and to about the top of said water-tubes and dividing said compartment into two chambers, said wall terminating short of the top of said compartment, a 40 grate in one of said chambers below said tubes, means below the tubes in the other chamber to co-operate with fuel therein in a manner to facilitate its combustion, a discharge-flue for and connecting with the upper 45 portion of each of said chambers, dampers for said flues, a baffle in each of said chambers depending from the tops of the respective chambers and extending down between 50 the tubes in such chambers, said baffles having ports therethrough, dampers in said ports, and means connecting each of said discharge-flue 55 dampers with the baffle-port damper of the remote chamber, whereby each such pair of dampers will open and close together.

In witness whereof I have hereunto set my hand.

ADOLPH T. JOHANSON.
